SUCTION CUP

Filed Nov. 14, 1931

Inventor,

Oliver C. Ritz-Woller,
By Trickey & Bawask,
Attorneys.

UNITED STATES PATENT OFFICE

OLIVER C. RITZ-WOLLER, OF CHICAGO, ILLINOIS

SUCTION CUP

Application filed November 14, 1931. Serial No. 575,052.

My invention relates to suction cups and has for its object the provision of a new and improved form and arrangement of parts by the use of which a supply of non-volatile sealing agent may be insured between the cup and the surface upon which the cup is used for preventing the leakage of air into the cup. It is one of the objects of my invention to provide a construction of this type in which a collapsible pocket or chamber is provided for the sealing agent so arranged and positioned that upon the application of the cup into holding position by pressure thereon the pocket shall be collapsed for forcing out the sealing agent into effective sealing position. To this end, it is one of the objects of my invention to provide an arrangement in which the means providing the pocket projects more or less into the concavity of the dished disc comprising a part of the cup so as to insure at least a partial collapsing of such chamber when the cup is applied. It is another object of my invention to provide an arrangement by reason of which a way of escape for the sealing agent from the pocket into the space thereabout may be maintained when the cup as a whole is distorted and flattened against the surface to which the cup is being applied by reason of the pressure necessary for applying the cup into holding position.

It is another object of my invention to improve devices of this type in sundry details hereinafter pointed out. The preferred means by which I have accomplished my several objects are illustrated in the accompanying drawings and are hereinafter specifically described. That which I believe to be new and desire to cover by Letters Patent is set forth in the claims.

In the drawings,—

Fig. 1 is a side view of my improved cup shown in applied position upon a plate glass such as the windshield of an automobile;

Fig. 2 is a side view of a similar cup in applied position upon a part such as the fender of an automobile;

Fig. 3 is a side view of my improved cup in normal condition before application into holding position;

Fig. 4 is a bottom face view of the device as shown in Fig. 3;

Fig. 5 is a vertical sectional view taken at the line 5—5 of Fig. 3;

Fig. 6 is a vertical sectional view similar to Fig. 5 but showing the changed position of the parts when the cup is applied into holding position upon a smooth surface;

Fig. 7 is an enlarged detail being substantially a section at line 7—7 of Fig. 5;

Fig. 8 is a view similar to Fig. 3 but showing an additional cooperating part; and

Fig. 9 is a view similar to Fig. 5 but showing a modified form of construction.

Referring now to Figs. 1 to 7 of the drawings, in which corresponding parts are indicated by the same reference characters, 15 indicates the dished disc portion of one of my improved devices secured in holding position upon a piece of plate glass 16, the disc portion 15 being provided with a body portion 17 on its outer face, with a bail 18 supported from the body portion 17.

In Fig. 2 I have shown an alternative use of one of my improved devices in which a standard 19 is mounted by means of a socket member 20 upon the body 17 of the device for holding the standard in upstanding position.

My device is preferably formed of comparatively soft rubber, the dished disc portion 15 being formed integrally with the body portion 17, as is clearly shown in Fig. 5. At the center of the disc portion 15 at the concave side thereof, I have provided a chamber or pocket 21 the outer portion of which is formed with comparatively thin pliable rubber wall portions 22 so as to be readily collapsible. As is clearly indicated in Fig. 6, when the device is compressed by its application to a surface such as the surface of the plate 23, the walls 22 are pressed inwardly so as to very materially diminish the size of the chamber 21. The device as a whole is further distorted so as to cut down very materially the effective size of the annular groove 24 between the walls of the chamber and the adjacent surface portions of the disc 15. Under such circumstances, the wall portions 22 are pressed very firmly against the surface of the plate 23, with the result that the open-

ing 25 leading from the chamber 21 would be closed by contact with the face of the plate 23 if it were not for the provision of the grooves 26 leading from the outer end of the opening 25 to the annular groove 24.

With the parts in the condition as illustrated in Fig. 5, a supply of any suitable non-volatile sealing agent is to be forced into the chamber 21, whereupon a plug such as the

10 part 27 is to be inserted into the opening 25 for preventing the escape of the sealing agent. In Fig. 8 the sealing agent within the chamber 21 is indicated by reference numeral 28. When the cup as shown in Fig.

15 8 is to be applied in holding position upon a surface, the plug 27 is to be removed, whereupon the required pressure is to be applied to the outer face of the cup for pressing the air out of the dished disc member. As is

20 above explained, the application of this pressure to the device serves to collapse the chamber 21, serving to force at least a portion of the sealing agent out of the chamber through the opening 25. Even when the device is

25 pressed to the limit of its motion toward the plate upon which it is being applied a way of escape for the sealing agent is still maintained by reason of the fact that the grooves 26 and 24 are still in communication with the outer end of the opening 25. The result is that the sealing agent is distributed by pressure along the grooves and is spread by such pressure quite completely over the face of the disc 15.

30 In the construction shown in Fig. 9, the outer wall portion 22 of the pocket or chamber is formed imperforate, the opening 25 being omitted while the construction remains otherwise the same. In this construction the non-volatile sealing agent 28 is inserted hypodermically, the resiliency of the material of the wall of the chamber being sufficient for closing the opening into the chamber after the withdrawal of the hypodermic

40 needle. In this arrangement the sealing agent is preserved very effectively for an indefinitely prolonged period in condition to be efficient for use. When the device of Fig. 9 is to be applied, the outer wall 22 is to be

45 perforated at any desired point along one of the grooves 26 so as to prepare the device for application to a surface with the assurance that the sealing agent will be forced out into position on the inner face of the disc 15 by the pressure incident to the application of the device to a surface.

50 The sealing agent employed may be silicone of soda, shellac, vaseline, glycerine, or any other suitable material.

55 Suction cups embodying my improvements may be supplied with the sealing agent at the factory, and since the agent is effectively sealed in, the devices may be stocked by distributors or dealers for long periods of time without the agent deteriorating or leaking

out. Thus it is possible for any person to purchase a suction cup containing the proper amount of a suitable sealing agent and in a moment's time put it into use.

While I prefer to employ the form and arrangement as illustrated in my drawings and as above described, it is to be understood that by invention is not limited to such form except so far as the claims may be so limited by the prior art, it being understood that changes might well be made from the form as shown without departing from the spirit of my invention.

I claim:—

1. A suction cup comprising in combination a pliable dished disc of resilient material, means on the outer face of the disc serving as an attachment means for an article to be supported, and means providing a chamber on the inner face of the disc extending somewhat into the concavity of the dished disc so as to insure the application of pressure thereon when the cup is being pressed into operative holding position on a surface. 80

2. A suction cup comprising in combination a pliable dished disc of resilient material, means on the outer face of the disc serving as an attachment means for an article to be supported, and means providing a chamber at the inner face of the disc and 85 having a collapsible portion extending into the concavity of the dished disc. 90

3. A suction cup comprising in combination a pliable dished disc of resilient material, means on the outer face of the disc serving as an attachment means for an article to be supported, means providing a chamber at the inner face of the disc extending into the concavity of the dished disc so as to be compressed when the cup is pressed into operative holding position on a surface, and means for closing a restricted opening into said chamber. 100

4. A suction cup comprising in combination a pliable dished disc of resilient material, means on the outer face of the disc serving as an attachment means for an article to be supported, and means providing a chamber at the inner face of the disc extending into the concavity of the dished disc so as to be compressed when the cup is pressed into operative holding position on a surface, the projecting portion of said chamber having a restricted opening therethrough with its outer end arranged to communicate 110 with a groove formed in the inner face of the disc and extending about said projecting portion so as to provide a means of escape for a supply of sealing agent from the chamber to the face of the disc when the cup is pressed firmly against a surface for suction attachment thereto. 115

5. A suction cup comprising in combination a pliable dished disc of resilient material, means on the outer face of the disc 120

6 serving as an attachment means for an article to be supported, and means providing a chamber at the inner face of the disc extending into the concavity of the dished disc so as to be compressed when the cup is pressed into operative holding position on a surface, the projecting portion of said chamber having a restricted opening therethrough and the outer face of said projecting portion 10 being provided with a groove leading from the outer end of said opening to an annular groove extending about said projecting portion.

6. A suction cup comprising in combination a pliable dished disc of resilient material, means on the outer face of the disc serving as an attachment means for an article to be supported, and means providing a chamber at the inner face of the disc extending into the concavity of the dished disc so as to be compressed when the cup is pressed into operative holding position on a surface, the projecting portion of said chamber having a restricted opening therethrough and 20 the outer face of said projecting portion being provided with a groove leading from the outer end of said opening to a groove formed in the inner face of the disc and extending about said projecting portion so as to provide 25 30 a means of escape for a supply of sealing agent from the chamber to the face of the disc.

7. A suction cup comprising in combination a pliable dished disc of resilient material, 35 means on the outer face of the disc serving as an attachment means for an article to be supported, and means providing a completely closed chamber at the inner face of the disc and having a collapsible portion extending 40 into the concavity of the dished disc.
